WIRE CONNECTER TOOL

Joseph R. Halladay, Alliance, Ohio, assignor to
 James R. Kearney Corporation, St. Louis, Mo.,
 a corporation of Missouri

Application September 12, 1932, Serial No. 632,775

13 Claims. (Cl. 81—3)

This invention relates to improvements in wire connecter tools, and more particularly to an improved tool or wrench for the remote connection of threadedly engageable members, to be used for example in applying wire connecters of split-bolt type.

An object of the invention is attained in an improved device of remotely-actuated type, for applying wire connecters, and so designed that connecting devices of so called solderless type may be applied with ease to the conductors of hot or live lines, with safety to the operator or line-man.

A further object of the invention is attained in an improved remotely-actuated wrench, for the application and removal of bolt and nut connections to electrical conductors generally.

A still further object of the invention consists in the provision of an improved wrench or tool, embodying, in a compact structure, a pair of wrench members, together with means for clampingly actuating the work to fix its position relative to the wrench members.

A still further object of the invention is attained in an improved tool for the purposes noted, including insulated means for the remote relative rotation of paired wrench members, together with a clamp for a wire or conductor to be positioned for connection by manipulation of the wrench member.

Yet another object of the invention is attained in a tool for the remote assembly of nuts and bolts to work to be connected thereby, such tool including means for remotely effecting a relative rotation between the bolt and nut, to effect threading thereof; means for effecting a relative axial movement of the bolt and nut to bring them into threading relation, together with a clamp for the parts to be secured together, by the threaded members.

The foregoing and many other objects will more fully appear from the following description of a preferred example of the invention, considered in connection with the accompanying drawings, in which:

Fig. 1 is a longitudinal sectional elevation through a clamping head or frame of the tool; Fig. 2 is a fragmentary sectional elevation of the device as viewed along line 2—2 of Fig. 1; Fig. 3 is a longitudinal section through a bolt-holding member, or socket, Fig. 3 being taken along line 3—3 of Fig. 1; Fig. 4 is a side elevation of a wire clamp, employed for positioning the tool and one or more conductors relative to each other for application of a connecter, and Fig. 5 is a fragmentary side elevation of the head or frame, as viewed from line 5—5 of Fig. 4.

Referring generally to the drawings, it is noted that the device of my invention, in its presently preferred embodiment, includes a clamping frame or head, by which is carried paired selectively spaced and aligned socket members, one of which serves for the reception of a bolt, and the other for a nut to be threaded onto the bolt. The device also includes means whereby the socket members may be relatively rotated; in the present example an insulated handle extends dependingly from the frame for rotating the nut-engaging socket, a second insulated handle being provided which serves the combined purpose of manipulating the bolt-receiving socket to and from the nut socket, and serves, separately, the purpose of actuating the wire engaging clamp. Many advantageous features and details of construction will appear from a description of the device by characters of reference appearing in the drawings, there being indicated, generally, at 6, a head or frame structure preferably formed of a metal casting, and provided with spaced aligned bores 8, at the upper or outer end of the frame and 10, at the inner or lower end thereof. The bore 8 constitutes a slide or guide for receiving a double-ended socket member 12 provided at its ends with bolt or nut receiving sockets 14 and 16 of dissimilar size, so that, by reversal, the member 12 may be brought to engage bolts of different sizes. The bore 8 is provided with a longitudinal opening 18 through which projects at a right angle to the socket member 12, an arm 20 having a right angular shank or rod portion 22 adapted for sliding movement in a bore or passage 24 formed longitudinally of the head or frame. The socket member 12, of which a plurality may be provided to care for different sizes of nuts and bolts, is provided with a transverse or diametral opening or passage 26 serving to receive the arm 20. Since the arm 20 precludes axial rotation of the socket member 12 within the passage or bore 8, no spline or keyway is necessary, and since the socket 12 is positioned along the bore 8 by the parts 20 and 22, no set screw or similar securing expedient is necessary to connect the socket 12 to the arm 20.

Journalled for rotation in the bore 10, is a pin or stub shaft 28 provided with a shouldered portion 30 overlying a bracket 32 formed as a part of the head, and connected as by a pin 34 to an extension piece 36 provided at its inner or lower end with a polygonal, preferably hex-

agonal head 38. A collar or ferrule 40 is provided internally with corresponding polygonal surfaces and is also pinned or secured to an insulating handle 42. The outer end of the ferrule 6 or collar 40 is enlarged with respect to the extension 36 so that the handle 42 may have, within limits, a universal angular adjustment with respect to the axes of parts 36 and 28. It will appear that the securement of the collar 30 and 10 extension 36 to the pin 28, precludes endwise movement of the pin in the bracket 32. A polygonal or squared extension of the pin 28, overlies the collar 30 and serves internally to engage, and rotatively to actuate a nut-receiving 15 socket member 44. As a means of positioning the socket member 44 endwise with respect to the frame, while permitting its rotation, the illustrated example employs a spring pressed arm 46 (Fig. 2) carried by a pivot 48 on the bracket 32, 20 and provided with a notched end 50 engaging a peripheral groove or recess 52 in the socket member 44. This arrangement constitutes a quick detachable connection permitting the use of any one of several socket members 44 for different 25 nut sizes; release and replacement thereof being effected by movement of the free end of lever 46 against the spring to release the notched end 50 from the groove 52.

As best appears from Fig. 1, illustrating the 30 tool as utilized for threading up a connector of split-bolt and nut type, the split bolt A and the nut B are engaged, respectively, by the socket members 12 and 44. For the purpose of causing the bolt to be retained by the socket 12, with 35 the bolt in inverted position, there is provided in the outer surface of the socket a longitudinal groove 54, in which are seated leaf spring members 56, secured as by screws to the body of the member, and provided with inwardly and radially extending spring fingers 58, each of which serves to engage laterally the head portion of a bolt inserted in one of the sockets, so that the bolt is thus releasably and frictionally supported in the position shown in Fig. 1.

45 Obviously, it is necessary, in order to bring the bolt A and nut B into thread-starting position, to effect an axial movement thereof one toward the other. This is accomplished in the present example by movement of the rod or shank 22, 50 endwise of the frame, and through the passage 24; the rod 22 being extended inwardly beyond the frame proper and into a metal ferrule or socket 60, this socket being in turn provided with, and pinned to an insulated handle 62. The 55 handle, socket and rod 22 are secured together against endwise or axial movement, as by a pin 64 extended transversely into a peripheral groove 66 near the inner end of the rod. It will appear that through vertical movement of the handle 62, the rod 22 may be moved endwise through the frame in a position to bring the bolt A into thread-starting relation with the nut B.

A desirable provision for clampingly engaging 65 one of the paired conductors to be connected by the use of the device, is best seen in Figs. 2 and 4 as including paired wire-clamping jaws 70, between which is clampingly engaged by knurled surfaces, a tap conductor such as C. The jaws 70 are pivoted, as by pins 72, to an extension piece 74 70 clamped to the frame 6 as by screws 76, the extension piece 74 preferably substantially enclosing the jaws except for their free or clamping ends. Actuation of the jaws is effected as by a vertically movable plunger 78, guidingly positioned for rectilinear movement within the extension 74. The 75

plunger 78 is provided with recesses 80 adapted to receive camming fingers 82, the outer end face of the plunger engaging similar camming surfaces 84 formed internally of the free ends of the jaws. The inner end of the plunger 78 projects free of the extension 74 and is pivotally connected to a rocker 86 carried by a fixed pivot 88, and provided with a forked end 90 embracing a threaded extension 92 of the frame 6, particularly the passaged portion 24 thereof. A nut 94 externally engages 10 the threaded extension 92 and is provided with diametrically opposed notches or kerfs 96 adapted to receive projections 98 on the ferrule or collar 60 of the handle 62.

It will appear that, by movement of the parts 15 62, 60 and 22, axially, into a position to bring the projections 98 into the notches 96, rotation of the handle 62 will serve to rotate the nut 94, bearing outwardly or upwardly on the forked end 90 of lever 86, and through coaction of parts 82 and recesses 90 of the clamping jaws and plunger, will serve to actuate the jaws 70 into clamping position. The opposite actuation of the jaws, when the nut 94 is backed off, is effected by a spring 20 pressed plunger 100 disposed in a socket therefor 25 in the bracket 32, and bearing against the forked end of the lever 86, so as to keep such end against the nut 94, as it is unthreaded along the shank 92. The resulting upward or outward movement of plunger 78 through the coaction of recesses 80 and camming fingers 82, serves to open the jaws 70 for 30 purposes of release of the clamp.

It will have appeared from the foregoing description of the tool, and the type of connector 35 preferably employed therewith, that a device of this order will have a frequent application in the assembly of a split-bolt type connector in attaching a tap conductor to a through run conductor. When so utilized, the split bolt A is positioned 40 within, for example, a socket 16 of the member 12 45 as shown in Fig. 1; the nut assembly including a washer having a diametral wire seat portion and indicated generally at E, is inserted in the socket of member 44, it being understood that the washer portion and wire seat carried thereby are rotatable within and relative to the nut. The end of a tap conductor, such as wire C, is then inserted 50 between the jaws 70 of the clamp, the jaws being actuated toward and into wire gripping relation by movement of the handle 62, and the free end of the tap conductor being extended sufficiently beyond the clamping jaws so as to overlie the wire seat of the washer E. The tool is then raised to a position somewhat above the through run conductor such as D (Fig. 1), and the handle 62 is 55 moved endwise, outwardly or upwardly, to bring the socket member 12, together with the connector bolt A, to lie entirely within the guide passage 8. The outer end of the frame 6 is then brought 60 downwardly or toward the through run conductor D, which is guided toward a wire seat 102 in the head by convergent wire-guiding fins 104, these being disposed in spaced pairs, with one pair on each side of the wire seat 102. Thus, as the head or frame is hooked over the through run conductor, the tool and wire will be directed relative to each other to bring the wire D to engage the seat 102. With the parts thus positioned, handle 62 65 is moved axially, in an inward or downward direction, so that the split bolt A is brought to overlie the through run wire. The wire D, seated in the bolt A, is now brought downwardly, relative to the frame, by further downward movement of handle 62 to a position where threading of the bolt and 70 nut may be initiated. This operation is effected 75

75

by rotation of insulating handle 42, resulting in rotation of socket 44 containing the nut, and is continued until the nut and bolt are firmly threaded up, and the tap wire C securely fastened to the through run wire D. The bolt A, being frictionally retained by spring end 58 up to this point, and now being securely held to the conductor D, the socket 12 may be released from the bolt by an upward or outward axial movement of handle 62 which serves, as will appear, to release the entire connector from the sockets and frame of the tool. The tool, however at this time remains secured to the tap conductor through the clamping jaws 70. The same upward movement which draws the socket 12 away from the connector bolt, serves to bring the lugs 92 into notches 96 so that appropriate rotation of handle 62 is then utilized to back off the nut 94, and thus to release the tap conductor from the jaws 70, following which the tool is entirely free of the wires and connector.

The handles 42 and 62 may obviously be of any desired length and are preferably formed of an insulating material such as wood, treated suitably to prevent absorption of moisture, although any other suitable material may be employed. The frame or head 6 is preferably formed, together with the bracket 32 and other extensions, of a casting, to insure its rigidity and the alignment of the sockets for receiving the nut and bolt of the connector. A wide selection of materials and a wide variation in design is, of course, possible within the scope of the invention, since numerous changes may be made without departing from the spirit and principles of the present disclosure, these being more fully defined by the claims hereunto appended.

I claim as my invention:

1. In a device for applying wire connectors of bolt and nut type, a frame having a lateral opening, aligned wrench members disposed at opposite sides of said opening and adapted, respectively, for engaging a bolt and nut of the connector to be applied, means for reciprocating one of said wrench members toward and from said wire opening, means for rotating one of the wrench members to effect threaded connection of the connector-bolt and -nut, a wire-receiving seat formed on said frame adjacent said opening, and wire guiding members, directed from said opening toward said seat.

2. In a device for applying wire connectors of bolt and nut type, a clamping head having a transverse wire-receiving seat, a wrench member reciprocable toward and from said wire seat, a wrench member rotatable in a plane transverse to that of a wire in said seat, a wire clamp carried by the frame, and positioned adjacent said rotatable wrench member, and means for remotely actuating said wrench members and clamp.

3. In a device for applying wire connectors of bolt and nut type, a frame, a pair of wrench members associated with the frame, a wire seat extended transversely of the frame, wire directing surfaces sloped toward said seat, a guideway formed longitudinally of the frame for receiving one of said wrench members, a second guideway in said frame, a slide in said last named guideway and having connection with said last named wrench member, a second wrench member, a rotatable mounting therefor arranged coaxially with said first named guideway, a wire clamp adjacent said rotatable mounting, and insulated handled extensions adapted for the rotation of said last named mounting, and for the move-

ment of said first named wrench member in the guideway therefor.

4. In a device for applying a wire connector of split bolt and nut type, to energized conductors, a frame having an upper longitudinal guide passage therethrough terminating inwardly in a wire seat of a trend transversely of the frame, paired convergent wire guiding elements at opposite sides of said wire seat and adapted to direct the frame into seating relation with one wire, a bolt-receiving socket member disposed in said guide passage and adapted to be reciprocated therein, said passage provided with a longitudinal slot, an arm engaging the socket member and extending laterally therefrom through said slot, and a rod extending from said arm, and longitudinally in guided relation through said frame, an insulating handled connection to the lower end of said rod, at a point below and beyond said frame, a second socket member, a drive shaft therefor journaled in said frame and having its axis aligned with said first socket and the passage therefor, an insulated handled extension for rotating said last named socket member and projecting below and beyond the frame, latching means for detachably connecting the last named socket to the shaft therefor, a tap wire clamp assembly mounted laterally of the frame and so located as to bring a tap wire held thereby into parallelism with a wire engaging the wire seat on said frame, a plunger disposed between, and in operative relation to the jaws of said clamp, a rocker pivoted to said frame and adapted for actuating said plunger, and means adapted upon rotation of the first said handled extension to actuate said rocker to effect a clamping movement of said clamping jaws.

5. In a tool for applying a wire connector of split bolt type, a frame structure including a tubular portion terminating at one end in a substantially V-shaped recess defining a transverse wire seat, a socket member disposed for sliding movement in the tubular portion, toward and from the wire seat, an elongate handle connected to said socket member, a second socket member coaxial with the first, rotatably mounted on the frame, and a second elongate handle operatively connected to said second socket member.

6. In a tool for applying a wire connector of split bolt type, an elongate handle, a socket member carried by, and held against movement relative to the handle, a head member mounted for longitudinal movement on the handle, said head member having a bore in which the socket member is disposed for longitudinal sliding movement, a second socket member, coaxial with the first, rotatably mounted on the head member, means for rotating the second socket member, said head member having converging surfaces at one end of said bore which define a wire seat of a trend transversely of the axis of said socket members.

7. In a tool for applying a wire connector, an elongate handle, a head member mounted for longitudinal sliding movement on the handle, said head member having a tubular portion parallel to, and laterally offset from the axis of the handle, means forming a transverse wire seat at one end of the tubular portion, a wrench member disposed for longitudinal movement in said tubular portion, operatively connected to said handle, a rotatable socket on the head member, coaxial with said wrench member, and means for rotating said socket.

8. In a tool for applying a wire connector including cooperating threaded elements, a tool

head embodying laterally spaced, relatively parallel tubular portions, an elongate handle extending longitudinally through one of said tubular portions, a socket member for engaging one 5 of the threaded connector elements, disposed for sliding movement in another of said tubular portions, operatively connected to said handle, a second socket member on the tool head for operatively engaging the other of said threaded 10 connector elements, said last recited tubular portion having means at one end thereof forming a wire seat, adapted to position a wire transversely between the socket members.

9. In a device for applying a wire connector 15 of split bolt and nut type, a frame having a guide passage therethrough terminating at one end in a wire seat of a trend transversely of the passage, paired convergent wire guiding elements at opposite sides of said wire seat, adapted to 20 direct the frame in seating relation with a wire, a bolt-receiving socket member disposed in said guide passage and adapted to be reciprocated therein toward and from said wire seat, said passage being provided with a longitudinal slot, 25 an elongate handle having a laterally projecting portion extending through said slot and engaging said socket member, a nut-receiving socket mounted for rotation on the frame, and actuating means for the nut-receiving socket.

30 10. In a device for applying a wire clamp of bolt and nut type, a frame, a wrench member mounted for rotation on the frame, a tubular sleeve integral with the frame, a second wrench member disposed in said sleeve for reciprocating 35 movement toward and from said first wrench member, means for preventing rotational movement of said second wrench member relative to the frame, means on said sleeve forming a transverse wire seat between said wrench members 40 and a pair of elongate handles, each thereof be-

ing operatively connected to one of said wrench members.

11. In a device for applying a wire clamp of bolt and nut type, an elongate handle, a frame 5 mounted for longitudinal sliding movement on said handle, a wrench member connected to said handle and mounted for reciprocating movement on said frame, a second wrench member aligned with the first recited wrench member rotatably mounted on said frame, a second elongate handle operatively connected with said second wrench member, and means on said frame forming 10 a seat for positioning a wire in right-angular, intersecting relation to the axis of the aligned wrench members. 15

12. In a device for applying a wire connector of bolt and nut type, an elongate handle, a frame 20 mounted for longitudinal sliding movement on said handle, means on the frame forming a guideway of trend parallel to the axis of said handle, means on the frame forming a wire seat 25 of a trend transversely to the trend of said guideway, a wrench member operatively connected to said handle and movable along said guideway, a second wrench member rotatably mounted on the frame, and operating means for said second wrench member.

13. In a device for applying a wire connector of bolt and nut type, an elongate handle, a frame 30 mounted for movement along the handle, said frame embodying a tubular portion terminating at one end in a transverse wire seat, paired converging wire guiding elements at opposite sides of said wire seat, adapted to direct the frame in seating relation with a wire, a wrench member 35 operatively connected to said handle and mounted for reciprocating movement in said tubular portion, a second wrench member rotatably mounted on said frame and means for remotely actuating said second wrench member. 40

JOSEPH R. HALLADAY.
